UNITED STATES PATENT OFFICE.

LUTHER S. SHAW, OF DETROIT, MICHIGAN.

BOILER ARCH AND WALL AND MEANS FOR SUPPORTING SAME.

1,345,410.

Specification of Letters Patent.

Patented July 6, 1920.

Application filed May 31, 1919. Serial No. 300,897.

To all whom it may concern:

Be it known that I, LUTHER S. SHAW, citizen of the United States, residing at Detroit, county of Wayne, State of Michigan, have invented a certain new and useful Improvement in Boiler Arches and Walls and Means for Supporting Same, and declare the following to be a full, clear, and exact description of the same, such as will 10 enable others skilled in the art to which it pertains to make and use the same, reference being had to the accompanying drawings, which form a part of this specification.

My invention relates to boiler settings, but 15 more particularly to means for supporting the roofs, arches and side walls,—the same being constructed of unburned fire brick while the latter is in a fickle condition,—and also for permanently suspending the same 20 after the fire brick material has been duly “burned.”

One object of the invention is to provide means, in combination with permanent 25 hangers, adapted to support channel irons, metal lath and paper to serve as a form for the unbaked fire brick material to hold it in place while baking.

Another feature of the invention consists 30 in providing tubular bolts (through which air may circulate to prevent warping and burning of the metallic parts) suspended from Z-beams or other suitable structural members—the bolts being provided with relatively large nuts or disks, secured thereon for permanently supporting the arch or 35 wall when baked;—removable tubular bolts being screwed into said nuts to support channel irons on which is laid metal lath and paper for supporting the firebrick material when in a formative condition,—said 40 supporting elements being removed when the fire brick material has been duly baked.

Another feature of the invention consists in surrounding all metals embedded in the 45 fire brick material with ferrules, gaskets or washers of flexible material such as paper felt. Another feature consists in providing for lowering the arch on to the permanent hangers for support after “baking.”

50 Another feature of the invention consists in providing a flexible connection between the bolts employed to permanently sustain the arch and those used for temporarily sup-

porting the platform on which the fire brick material is laid before “burning.”

Another feature of the invention consists in suspending the permanent hangers by a nut adapted to tilt upon the flange of the supporting rail, that the fire brick material may be relieved of any strain occasioned by a hanger rigidly secured to the supporting rail.

Another feature is the closure of the holes in the fire brick wall upon the removal of the temporary supporting bolts.

Another feature of the invention is the driving out of said plugs by the insertion of a suitable tool in the permanent tubular bolts above the temporary bolts;—that channels, lathing and paper may be again installed for the purpose of making repairs.

Another feature of the invention consists in providing “ventilating” washers and nuts for the passage of air whereby the parts may not warp or injure the fire brick wall 75 while baking the latter.

Another feature of the invention consists in providing suitable expansion joints in the fire brick material to further protect the walls against injury during the baking 80 process.

Another feature of the invention consists in the manner of supporting the roof and side walls of inclined or V-type stokers.

Another feature of the invention consists in providing means whereby the side walls may be raised from the magazine for repairs, the same being subsequently lowered into their former position.

Another feature of the invention is to 90 prevent the side walls tipping or sliding into the furnace.

Another object is to take the weight of the side walls off the iron work of the stoker magazine.

Another feature of the invention is the method of constructing and supporting an arch suitable for the rear end of a return tubular boiler.

With the foregoing and other objects in view which will appear as the description proceeds, the invention resides in the combination and arrangement of parts and in the details of construction hereinafter described and claimed, it being understood 100 that changes may be made in the precise

embodiment of the invention herein shown and described without departing from the spirit of the same.

In the drawings accompanying this specification:—

Figure 1 is a longitudinal vertical sectional view of a boiler setting showing my invention installed.

Fig. 2 is a cross-sectional view on line 10 2—2 of Fig. 1.

Fig. 3 is a fragmentary longitudinal vertical sectional view through the front arch, as when finished.

Fig. 4 is a cross-sectional view on line 15 4—4 of Fig. 3.

Fig. 5 is an enlarged cross-sectional detail on line 5—5 of Fig. 4.

Fig. 6 is a cross-sectional view through a V-type stoker furnace—showing the manner of suspending the arch and vertical side walls.

Fig. 7 is a cross-sectional view also taken on line 4—4 of Fig. 3, showing the temporary means employed for supporting the arch while the fire brick material is in a 25 fragile condition.

Fig. 8 is an enlarged sectional detail view showing the tubular bolts for temporarily, and for permanently suspending the arch, 30 the flexible connection between the bolts, and also the vents through the bolts and supporting disks and nuts, to provide for the circulation of air therethrough.

Fig. 9 is an enlarged sectional detail view, 35 showing a tool inserted in the tubular bolt for driving out the plug in the arch, that the supporting means shown in the preceding view may be installed for making repairs in the arch.

40 Referring now to the letters of reference placed upon the drawings:—

A, denotes a boiler. B, the usual brick side walls or setting for supporting the same. C, are Z- or other suitable beams supported by the side walls of the boiler setting.

D, denotes a plurality of tubular bolts, spaced apart and suspended by nuts D', from the flange of the Z-beam C,—the head of the nut being preferably inverted in 50 order that its rounded face may permit of a slight swinging action of the bolt.

E, indicates a relatively large disk loosely secured to the bolts by expanding the lower end of the bolts, as indicated at a,—the disks being preferably arc-shaped on their upper face and provided with a plurality of ventilating holes E', through the wall of the disks for the passage of air.

F, are removable tubular bolts, screwed 60 into the respective disks, to provide a temporary extension of the bolts D, for supporting the channel irons G. H, indicates corrugated iron or expanded metal lath resting upon the channel irons, and I, is a paper

lining mounted upon the metal lath. J, indicates a felt or paper gasket or wrapping surrounding the bolts or disks.

K, denotes the arch formed of unburned fire brick laid upon the temporary sustaining members, but embedding the ends of the permanent supporting hangers or bolts. The form of the arch may be either flat, or arc-shaped as indicated in dotted lines in Fig. 7 of the drawings. The ends of the temporary supporting bolts F, are provided 75 with transverse holes F', and the ends of the bolts are fitted with an apertured plug F'', to reduce the opening so as to cause a circulation of air through the channel irons G, as well as throughout the bolts to thus insure 80 against warping or buckling of the parts.

Prior to baking the material forming the arch, the nuts on the lower ends of the bolts F, may be adjusted to slightly raise the fire brick material so as to take the load from 85 the permanent disks or washers E, until the arch has been properly baked.

The fire brick material forming the arch, having been properly shaped to meet the requirements of the installation upon the temporary supporting members, it is then baked and upon completion of the baking process, the temporary supporting members are removed, and the holes through which the bolts projected for suspending the latter 95 structure are then plugged up as indicated at L, in Fig. 5 of the drawings.

By suspending the bolts by nuts having a rounded face in contact with the supporting beam, provision has been made for a slight 100 rocking movement of the bolt which may occur due to the expansion or contraction of the fire brick material during the baking process, the latter is thus relieved of stress—which in a rigidly fixed bolt might cause 105 the fire brick material to crack.

A flexible connection between the end of the bolts D, and the disks E, is obtained by expanding the end of the bolt so as to engage the overlapping wall of the disk, the object 110 being to provide a yielding connection between the upper and lower bolts so as to relieve the fire brick material of the stress that would occur from a rigid connection and thereby overcoming any tendency of 115 the material to “crack” during the baking process.

It will be noted upon reference to Fig. 6 of the drawings that the bolts at the end of the supporting beam extend down into the 120 vertical side walls to support the latter, taking the weight of the side walls off of the iron work of the stoker magazine, the bolts also serving to prevent the side walls tipping or sliding into the furnace. By an 125 adjustment of the nuts from which the bolts are suspended, the side walls may be raised or lowered for repairs.

To provide for the expansion and contraction of the material forming the arch and side walls—expansion joints M, are provided, formed by inserting suitable 5 wedges in the unburned fire brick material.

When necessary to repair the arch, the 10 filler plug L, is first driven out by inserting a suitable tool N, in the bolts D. The extension bolts F, and removable platform are then connected with the permanent bolts 15 above as before, the necessary repairs being made with unburned fire brick material, supported as in the initial construction of the arch, by the removable platform until 20 burned;—the platform and bolts are then removed and the holes plugged as before.

While the invention has been described more particularly as applied to steam boiler furnaces, it is equally well adapted for use 25 in other forms of furnaces.

Having thus described my invention, what I claim is:—

1. In a boiler setting, the combination of a plurality of beams suitably supported, a 25 plurality of bolts suspended from said beams fitted with relatively large disks or nuts for supporting an arch or wall, a platform for temporarily supporting an arch or wall of unburned fire brick material, a plurality of bolts detachably connected with 30 said first named bolts by said disks for suspending the platform during the process of burning the fire brick material, and an arch or wall suspended from said first named 35 bolts, formed of unburned fire brick material upon said platform and baked while temporarily supported thereby.

2. In a boiler setting, the combination of a plurality of beams suitably supported, a 40 plurality of tubular bolts suspended from said beams, fitted with relatively large disks or nuts for supporting an arch or wall, a platform for temporarily supporting an arch or wall of unburned fire brick material, a plurality of extension tubular bolts 45 detachably connected with said first named bolts for supporting said platform during the process of burning the fire brick material, and an arch or wall permanently supported by said first named bolts, formed of unburned fire brick material upon said platform and baked while temporarily supported thereby.

3. In a boiler setting, the combination of a 55 plurality of beams suitably supported, a plurality of tubular bolts suspended from said beams and fitted at their upper ends with nuts having a rounded face in contact with the flange of the beams, disks loosely secured to the lower ends of the bolts for supporting an arch or wall, said disks having holes for the passage of air therethrough, extension tubular bolts temporarily connected with the first named bolts and fitted

with nuts below for supporting a plurality 65 of channel irons in spaced relation to the disks, channel irons temporarily supported by the last named respective bolts, a sheeting of metal covering said channel irons to form a platform, an arch or wall formed of 70 unburned fire brick material temporarily supported by said platform while being baked, and elastic wrappings surrounding said bolts and disks to maintain the fire brick material in spaced relation to said metallic 75 members.

4. In a boiler setting, the combination of a plurality of Z-beams, supported by the boiler setting, a plurality of tubular bolts suspended from the flanges of said beams, 80 disks provided with ventilating holes loosely secured to the lower ends of said bolts for supporting an arch, extension tubular bolts temporarily connected with the first named bolts, having transverse openings for the 85 passage of air, an apertured plug fitted to the end of said tubular bolts to reduce the longitudinal opening therethrough, whereby the air will pass longitudinally and transversely through said bolts, channel irons suspended by said last named bolts adapted to support a platform, a platform of corrugated metal supported by said channel irons, a fiber sheet mounted upon the corrugated iron, and an arch or wall formed of unburned fire brick material temporarily supported by said platform while being baked.

5. In a boiler setting, the combination of a plurality of beams suitably supported, a plurality of tubular bolts suspended from said 100 beams, a plurality of relatively large disks or nuts having a flexible connection with the respective bolts for supporting an arch or wall, a platform for temporarily supporting an arch or wall of unburned fire brick material, a plurality of extension tubular bolts 105 detachably connected with said disks or nuts for supporting said platform during the process of burning the fire brick material, an arch or wall permanently supported by 110 said first named bolts, formed of unburned fire brick material upon said platform and baked while temporarily supported thereby, and suitable parting strips embedded in said arch or wall whereby expansion joints may 115 be formed in the latter.

6. In a boiler setting, the method and process of suspending from an overhead structure an arch or wall of unburned fire brick material and afterward baking the 120 same in position, consisting in first mounting suitable supporting beams on the walls of a boiler setting adapted to support the arch or wall, suspending from said beams a plurality of hangers adapted to permanently 125 support the arch or wall, temporarily suspending a platform by detachable hangers connected with said first named hangers,

shaping an arch or wall out of unburned fire
brick material around said permanent sup-
porting hangers and upon the temporary
supporting platform, baking the unburned
5 fire brick material while supported by the
platform, then removing the platform and
temporary supporting hangers.

In testimony whereof, I sign this specifi-
cation in the presence of two witnesses.

LUTHER S. SHAW.
